CLAIM

We claim the ornamental design for a golf club head, as shown and described.

DESCRIPTION

FIG. 1 is a perspective view of a golf club head, as viewed from the top and one side;

FIG. 2 is a front elevation view of a golf club head of FIG. 1;

FIG. 3 is a rear elevation view of the golf club head of FIG. 1;

FIG. 4 is a side elevation view of a toe side of the golf club head of FIG. 1;

FIG. 5 is a side elevation view of a heel side of the golf club head of FIG. 1;

FIG. 6 is a top plan view of the crown of the golf club head of FIG. 1; and,

FIG. 7 is a bottom plan view of the sole of the golf club head of FIG. 1.

The broken lines in the drawings are for purpose of illustrating environmental structure as well as portions of the design that form no part of the present claimed design. The dash-dot broken lines (in FIG. 1 for example) represent an open boundary and form no part of the claimed design. The area within the oval dash-dot lines contains stippling representing one color on at least a portion of the crown and portion of the face, and a band of contrasting color therebetween.
